ELECTRIC SPACE HEATER

John C. Beckett, Kentfield, Calif., assignor to Wesix Electric Heater Co., San Francisco, Calif., a corporation of California

Application October 4, 1954, Serial No. 32,537

Term of patent 14 years

(Cl. D81—10)

FIG. 1

FIG. 2

Figure 1 is a perspective view of an electric space heater embodying my new design with the wire grill pattern partially shown. It is to be understood that the same pattern covers the entire grill; and

Figure 2 is a reduced side elevational view thereof. The other side not shown is the same as the side shown.

I claim:

The ornamental design for an electric space heater, substantially as shown and described.
